UNITED STATES PATENT OFFICE.

ROBERT LEE SKINNER, OF LE ROY, NEW YORK.

DOOR-LOCK.

1,087,193.

Specification of Letters Patent. Patented Feb. 17, 1914.

Application filed May 3, 1913. Serial No. 765,183.

To all whom it may concern:

Be it known that I, ROBERT L. SKINNER, of Le Roy, in the county of Genesee and State of New York, have invented certain new and useful Improvements in Door Locks; and I do hereby declare the following to be a full, clear, and exact description of the same, reference being had to the accompanying drawings, forming a part of this specification, and to the reference-numerals marked thereon.

My present invention relates to locks and more particularly to knob locks for doors, and it has for its object to provide a simple, cheap and efficient lock of the thrust spindle type so constructed that the increased friction resulting from the pressure on the door in opening and which must be overcome by the latch during its retracting movement is greatly reduced.

A further object of the invention is to provide a lock of this nature having a safety catch of an improved construction and possessing, among other advantages, characteristics whereby the catch may be set with the door open and the door then slammed and the latch locked against a second retraction until released by the manipulation of the safety catch mechanism.

To these and other ends the invention consists in certain improvements and combinations of parts all as will be hereinafter more fully described, the novel features being pointed out in the claims at the end of the specification.

In the drawings: Figure 1 is a horizontal section through a door lock constructed in accordance with and illustrating one embodiment of my invention, adjacent portions of the door and jamb being also shown and the parts being in normal position, that is, with the latch ready to be released by pressure on the knobs; Fig. 2 is a similar view with the latch retracted; Fig. 3 is a similar view with the latch in locked position and under the influence of the safety catch; Fig. 4 is a section taken substantially on the line 4-4 of Fig. 1; Fig. 5 is a section through the same parts taken substantially on the line 5-5 of Fig. 3; Fig. 6 is a section taken on the line 6-6 of Fig. 5, and Fig. 7 is a detail section taken substantially on the line 7-7 of Fig. 3.

Similar reference numerals throughout the several figures indicate the same parts.

Referring more particularly to the draw-

ings, A indicates the door, and B the door casing or jamb, the latter provided with the usual aperture C and keeper plate D. The door A is preferably bored out as at E to receive the main supporting member 1 of the lock mechanism. This supporting member preferably comprises in an integral piece an outer end plate 2 flush with the edge surface of the door and an inner ring 3 (Fig. 4) which hold the supporting member snugly within the bore E. The outer end plate 2 is apertured at 3^a to allow the projection therethrough of the outer end of the latch 4 which has an abrupt engaging face 5 and a beveled face 6 on the other or rear side, as usual. The inner end of the latch 4 has an angularly disposed portion 7 guided between two pins or projections 8 on the support 1, but the latch is normally held projected or in the position shown in Fig. 1 by a spring 9 of the compression type connected at its respective ends to the latch and support and preferably provided with a stiffening core 10 to prevent undue distortion thereof when compressed.

The door knobs 11 and their sleeves 12 are carried in fixed relation on a transversely disposed thrust spindle 13 guided in the escutcheon plates 14 of the door and provided at an intermediate point with a laterally projecting cam 15. Arranged in the path of this cam is an upstanding projection or abutment 16 at the inner extremity of the latch 4 and of the angularly disposed end portion 7 thereof.

In the operation of the lock as thus far described, when the door is to be opened it is only necessary to pull one knob 11 (the lower one in the figures) or push upon the other one, as the case may be, whereupon the cam 15 engages the projection 16 and forces it to the right from the position shown in Fig. 1 to that shown in Fig. 2, retracting the latch 4. As the latter is guided only by the end plate 2 of the support and the guide pins 8 and the portion 7 thereof that actually engages the guide pins is disposed angularly, the latch is given not only a reciprocatory movement but is at the same time swung or displaced laterally as shown in Fig. 2 or in a direction away from the engaging face 5. It will be noted in this connection that the lower guide pin 8 is arranged intermediate the outer end of the latch and the point to which the projection 16 is carried by the cam so that it acts as a

fulcrum to effect this swinging movement. Thus, as the pressure necessary to operate the spindle 13 is exerted against the knob and hence against the door and communicated to the latch in its engagement with the keeper plate D, the engaging face 5 of the latch is simultaneously caused to recede with the result that it disengages smoothly and easily. At the same time, the rear or 10 beveled face 6 is being backed up by the end plate 2 but as it presents an incline for this engagement it assists rather than retards the retracting movement as will be seen from inspection of Fig. 2. When the latch is in the 15 extended position of Fig. 1, however, the beveled face 6 is not in engagement with the end plate 2 but instead a squared-off side of the latch adjacent thereto so that there is no tendency for it to perform this retracting 20 function until after the movement has progressed some distance under the influence of the spindle 13 and cam 15 thereon.

The latch will be seen to be a spring latch, that is, one that yields with the closing of 25 the door independently of the knobs and automatically projects itself into engagement with the keeper plate to be thereafter released only by manipulation of the knobs. In this instance, the retraction of the latch 30 is effected in the ordinary manner by the riding of the incline 6 on the outer edge of the keeper plate.

In order that the latch may be locked in 35 its extended position beyond the control of the knobs to permit the door to be opened only from the inside or through the use of a key from the outside, what will be termed a safety catch mechanism is employed. This comprises a detent 17 carried, in the present 40 instance, by the latch itself on a pivot 18 (Fig. 4) and pressed downwardly by a spring 19 so that the normal tendency of the detent is to interlock at its ends with the spindle 13 by dropping into a depression 20 provided therein (see Fig. 5). This engagement prevents inward movement of the latch and also prevents any reciprocation of the 45 thrust spindle 13 as will hereinafter appear.

Extending longitudinally through the center of the spindle 13 and rotatable therein through 90° is a stem or controlling member 21. The spindle is preferably made in two parts in order that this stem may be inserted and the parts secured together by the sleeves 50 12 of the knobs 11 and also by pins 22 which also serve to secure the sleeves in fixed position on the spindle. On the inside of the door, the said stem may be rotated at all times by a finger portion 22^a projecting from the center of that knob whereas on the outside the spindle is slotted at 23 to receive a key so formed as to interlock with a correspondingly formed end portion 24 on the stem, the spindle being cut to form wards 55 25 as usually required in locks. In fact, the

said stem may be placed under the control of any particular kind of a key or lock mechanism suitable to the general structure shown and it is not thought that a specific construction need be described any further in detail. 70

The detent 17 is normally held in an inoperative position by a cam or eccentric 26 on the stem 21 which, together with an extension thereof constituting a dog 27, occupies the recess 20 as shown in Figs. 1, 2 and 4. When it is desired to bring the safety catch into 75 operation, and to lock the latch against retraction by the knobs, the stem 21 is rotated to the left which throws the cam 26 out of a portion of the opening 20 but which causes the detent 17 to be raised by the dog 27 and to be still held in an inoperative position. Besides its rotary movement, the stem 21 is also movable a limited distance longitudinally. Therefore, when the door is closed 80 and the latch automatically retracts itself during which movement the inner end of the latch moves laterally in its guide 8 in one direction while the outer end is tilted in the other as before described, the detent 17 slips off the dog and during the subsequent outward movement of the latch into engagement with the keeper the detent rides along against the flat surface 28 on one side thereof and finally drops into the recess 20 preventing 85 a subsequent retraction of the latch or reciprocation on the part of the spindle 13. 90

To release the latch from the safety catch, it is only necessary to rotate the stem 21 back to its former position either by means 100 of the finger portion 22^a on the inside or by the use of a key on the outside. The cam portion 26 will then ride the detent 17 out of the recess 20 as shown in Fig. 4 and at the same time a cam surface 29 on the edge 105 of the dog 27 opposite to the straight edge 28 thereof engages a cam surface 30 on the adjacent side of the recess 20 and returns the stem 21 in a longitudinal direction to its former position so that the dog 27 is brought back beneath the detent in readiness to raise it again, while the dog and cam 26 together completely fill the recess. Thus the safety 110 catch may be set with the door open and the door then slammed shut and locked automatically as only one reciprocation or retraction of the latch is permitted after this setting of the mechanism. Should it be desired, however, to set the latch while the door is closed, it is only necessary after raising the dog 27 to manually impart the longitudinal movement to the stem 21 that would otherwise be accomplished automatically by the detent either by pressing on the thumb piece 22^a or by moving the whole 125 spindle 13, which will ordinarily have enough play to carry the dog 27 from beneath the detent. In fact, the engagement of these two last named parts is required for only an instant as the detent travels be- 130

yond the recess 20 immediately the inward movement of the latch starts.

It will be observed that only the one spring is necessary for the whole mechanism as the projection 16 on the latch riding the cam 15 on the spindle returns the latter to a normal or central position. The thrust of the spindle in one direction is halted by this same engagement as the latch itself is in turn halted at the limit of its retracting movement by the engagement of a shoulder 31 thereon with one of the guide pins 8 as shown in Fig. 2, whereas in the other direction a stop 32 on the spindle is adapted to engage the portion 7 of the latch when the latter is fully extended.

I claim as my invention:

1. In a lock, the combination with a reciprocatory latch member having an abrupt engaging face for coöperation with the keeper plate and a transversely disposed thrust spindle operating to retract the latch member, of a guide for the latter adapted to effect a lateral displacement thereof coincidently with its longitudinal reciprocation whereby its engaging face is caused to recede from the keeper during the retraction of the latch.

2. In a lock, the combination with a reciprocatory latch having an abrupt engaging face for coöperation with the keeper plate and a transversely disposed thrust spindle operating to retract the latch member, of a guide for the latter coöperating with the inner end thereof and adapted to effect a lateral displacement of the latch, coincidently with its longitudinal reciprocation whereby its engaging face at the opposite end is caused to recede from the keeper plate during the retraction of the latch.

3. In a lock, the combination with an apertured supporting member, a reciprocatory latch member carried thereby having an outer end normally projecting through the aperture and provided with an abrupt engaging face on one side for coöperation with the keeper and a beveled face on the other side and a transversely disposed thrust spindle operating to retract the latch member, of a guide for the latter coöperating with the inner end thereof and adapted to effect a lateral displacement of the latch coincidently with its longitudinal reciprocation whereby the engaging face is caused to recede from the keeper plate during the retraction of the latch, the beveled face at its outer end being arranged to coöperate meanwhile with a wall of the aperture in the support to accelerate the retracting movement.

4. In a lock, the combination with a reciprocatory latch member having an abrupt engaging face at its outer end for coöperation with the keeper plate and a transversely disposed thrust spindle operating to

retract the latch member, of a guiding member coöperating with an intermediate portion of the latch and a part on the spindle adapted to engage the latch beyond the guiding member and to rock it on the latter to effect a lateral displacement of the outer end coincidently with its reciprocation whereby its engaging face is caused to recede from the keeper during the retraction of the latch.

5. In a lock, the combination with a reciprocatory latch member having an abrupt engaging face at its outer end for coöperation with the keeper plate and a transversely disposed thrust spindle operating to retract the latch member, said latch member and spindle being provided with coöperating abutments one of which has a cam face, of a guiding member on the support coöperating with a portion of the latch member intermediate the said abutment and the outer end of the latch member whereby the engagement of the abutment on the spindle effects a lateral displacement of the outer end of the latch member coincidently with its longitudinal reciprocation and its engaging face is caused to recede from the keeper during the retraction of the latch.

6. In a lock, the combination with a reciprocatory latch member and a transversely disposed thrust spindle operating to retract the latch member, of a safety catch embodying a detent carried on one of the members and adapted to interlock with the other whereby both the retraction of the latch and the thrust of the spindle is prevented.

7. In a lock, the combination with a reciprocatory latch member and a transversely disposed thrust spindle operating to retract the latch member, of a safety catch embodying a detent carried on one of the members and having off and on positions in which latter it is adapted to interlock with the other member whereby both the retraction of the latch and the thrust of the spindle is prevented, and a controlling device for the detent carried by the thrust spindle and arranged to hold the detent in one of its said positions.

8. In a lock, the combination with a reciprocatory latch and a transversely disposed thrust spindle operating to retract the latch, of a safety catch embodying a detent carried by the latch and having a normal tendency to interlock with the thrust spindle and a rotary controlling device extending through the spindle and embodying a cam operating to throw the detent to an inoperative position with reference to the spindle.

9. In a lock, the combination with a reciprocatory latch and a transversely disposed thrust spindle operating to retract the latch, of a safety catch embodying a detent carried by one of the parts and hav-

ing a normal tendency to interlock with the other, a controlling device operating to throw the detent to an inoperative position and means for automatically displacing the controlling means to allow the detent to assume an operative position upon the next reciprocation of the latch.

10. In a lock, the combination with a reciprocatory latch and a transversely disposed thrust spindle operating to retract the latch, of a safety catch embodying a detent carried by one of the parts and having a normal tendency to interlock with the other, a controlling device normally operating to hold the detent in its operative position, means set by the movement of the controlling device in one direction for automatically displacing the latter during the next reciprocation of the latch to permit the detent to assume an operative position and means for manually so displacing the controlling device independently of any reciprocation of the latch.

11. In a lock, the combination with a reciprocatory latch and a transversely disposed thrust spindle operating to retract the latch, of a safety catch embodying a detent carried by one of the parts and having a normal tendency to interlock with the other, a controlling device within the spindle normally operating to hold the detent in its inoperative position, means set by the rota-

tion of the controlling device for automatically displacing the latter longitudinally during the next reciprocation of the latch 35 to permit the detent to assume an operative position and means for manually so displacing the controlling device independently of any reciprocation of the latch.

12. In a lock, the combination with a reciprocatory latch and a transversely disposed thrust spindle operating to retract the latch and having a recess therein, of a safety catch embodying a detent carried by the latch and having a normal tendency to interlock with the spindle by engagement with the recess therein, a stem rotatably and longitudinally movable within the spindle and having a part thereon normally occupying the recess in the spindle to hold the detent 50 in its inoperative position, and a dog on the stem adapted to hold the detent in inoperative position when the stem is rotated to carry the said part thereon out of the recess, the detent being adapted to ride off of 55 the dog when reciprocated and to actuate the same laterally to move the stem longitudinally whereby the detent is permitted to engage within the recess and prevent subsequent reciprocation of the latch.
